METHOD OF MAKING BUNGS

Cleo E. Shepard, Chicago, Ill.

Application May 3, 1937, Serial No. 140,353

5 Claims. (Cl. 29—148.2)

This application is a continuation in part of my copending application Serial No. 66,142 filed February 28, 1936.

- The above identified copending application relates to a novel bung comprising a body portion formed from sheet metal, and a transverse handle member which is located within the body. The present invention relates to methods whereby such a bung may be made.
10. The invention will readily be understood from the following description, taken in conjunction with the accompanying drawing, in which:

Figure 1 is an elevational view, partly in cross section, of a set of dies suitable for making the improved bung body;

Fig. 2 is an elevational view, partly in cross section, of a similar die suitable for assembling the wrench engaging bar to the bung body;

Fig. 3 is an elevational view of a similar die, partly in cross section, suitable for forming the body of the bung and assembling the wrench engaging bar in the same operation;

Fig. 4 is a plan view of the blank from which the body of the bung is formed;

25. Fig. 5 is a plan view of a bung body;

Fig. 6 is a plan view of a bung body provided with a wrench engaging bar;

Fig. 7 is a plan view of the preferred form of the wrench engaging bar; and

30. Fig. 8 is an elevational view, partly in section, of the completed bung.

Referring to the drawing; in Fig. 1 the upper die consists of a ring 10 whose inside diameter 11 corresponds with the outside shape and diameter of the bung body desired. Inside this ring 10 is a member 12 which serves to eject the formed bung body. The lower die consists of a ring 13 which has a seat 14 to receive the blank 17 from which the bung body is made. The ring 13 rests 40 on pins 15 supported in turn by suitable compression means (not shown). The ring 13 surrounds a punch 16 of the shape and size of the inside of the bung body desired.

It will readily be understood by those skilled 45 in the art that the dies shown in Fig. 1 will operate on a blank 17 (Fig. 4) to provide a cup-shaped body such as is shown in Fig. 5. This body comprises a bottom portion 23, a cylindrical wall portion 24 extending upwardly therefrom, and a 50 peripheral flange 25 at the upper end of the cylindrical wall. This flange 25 may be of any conventional type such as the narrow undercut flange as shown in Fig. 8 or of the wider type to cover a wide flat gasket.

55. The bung described and claimed in my afore-

said copending application includes a bar or wrench engaging member 21, hardened or of harder material than the bung body, having relatively sharp corners 22. The preferred form of this bar is shown in Fig. 7, but it may have 5 ends shaped in various ways or may be made of folded sheet metal. This bar is somewhat longer, at least at its sharp edges, than the inside diameter of the cylindrical portion 24 of the bung body, so that when forced into the body 10, the corners 22 cut into the relatively softer stock of the bung body, with the result that the bar is rigidly mounted in place within the body and may be engaged by a wrench to apply torque for application to and removal from a bung hole. 15.

The bar 21 may suitably be applied to the bung body by means of the dies shown in Fig. 2. These dies are similar to those used for forming the body except that the seat 19 in the lower die ring 18 is made to fit the flange of the previously 20 formed body and the die punch 20 is slotted to receive the bar 21. A bung body as shown in Fig. 5, formed by the dies shown in Fig. 1, is set in the seat 19 after a bar 21 is centrally located in the slot in the punch 20. The top die is caused to 25 approach the lower die, and the body portion is forced into the ring 10. As the operation continues the body is forced over the punch 20 and at the same time over the protruding edges of the bar 21. The edges of the bar cut into the inside 30 cylindrical wall of the body. At the end of the operation the body wall is finished over the open ends of the slots so cut, so that these slots are deformed and closed, thereby permanently securing the bar in place within the body of the bung. 35

In a modified method of producing my improved bung, the body portion may be formed and the wrench engaging bar securely installed therein in the same and single operation. This may be done with the aid of the dies shown in 40 Fig. 3. For this purpose a bar 21 is centrally located in the slot in the punch 20, a blank is placed in the seat 14 in the ring 13, and the upper die is caused to approach the lower die. Thus the bung body is formed around the bar 45 and instead of the protruding edges being made to cut into the body wall the metal of the body is forced to flow around the protruding ends of the bar, so that when the forming of the body is 50 completed the bar ends are securely embedded in the walls of the body. The result is that the assembly is for all practical purposes identical with the assembly previously described.

The exact form of the bar ends is immaterial 55

but at its edges at least it must be longer than the inside diameter of the body portion.

After the bung is thus finished by either of the methods described, it can be threaded and if 5 desired an undercut gasket seat may be cut.

It is to be noted that I have produced a bung in an economical and simple manner from a sheet metal blank and a bar.

Having thus described my invention, what I 10 claim is:

1. The method of making a bung, which comprises making a cup-shaped member, making a bar that is substantially harder than the material of the cup and having sharp cutting edges 15 at its ends, the length of the bar between cutting edges on one side of the bar being slightly greater than the normal chord of the cup between the points where the cutting edges engage the cup walls when the bar is located diametrically within 20 the cup, forcing the bar into the cup diametrically across it so that the sharp edges of the bar are caused to cut into the walls of the cup throughout the distance the bar is inserted in the cup, the engaging of the ends of the bar and 25 the side walls of the cup preventing forced rotation of the bar in relation to the cup-shaped member.

2. The method of making a bung, which comprises making a cup-shaped member having an 30 externally extending peripheral flange at its open end, making a bar that is substantially harder than the material of the cup and having sharp cutting edges along its ends, the length of the bar between the cutting edges on one side being 35 slightly greater than the normal chord of the cup between the points where the cutting edges engage the cup walls when the bar is located diametrically within the cup, forcing the bar into the cup diametrically across it so that the sharp edges of the bar are caused to cut into the 40 walls of the cup throughout the distance the bar is inserted in the cup, the engaging of the ends of the bar and the side walls of the cup preventing forced rotation of the bar in relation to the cup-shaped member, and thereafter cutting a 45 screw thread on the external wall of the cup.

3. The method of making a bung, which comprises making a cup-shaped member, making a

bar that is substantially harder than the material of the cup-shaped member, the height of the bar being substantially equal to the depth of the cup, the ends of the bar being cut to form vertical sharp cutting edges for engagement with the 5 side walls of the cup, forcing the bar downwardly into the cup diametrically across it, the length of the bar between the cutting edges being slightly greater than the normal chord of the cup between the points where the cutting edges 10 engage the cup walls, so that the sharp edges of the bar are caused to cut into the walls of the cup substantially throughout the height of the cup and the bar, the engaging of the cup walls and the ends of the bar preventing forced rotation 15 of the bar in relation to the cup-shaped member.

4. The method of making a bung, which comprises making a cup-shaped member having an externally extending peripheral flange at its open 20 end, making a bar that is substantially harder than the material in the cup-shaped member, cutting the ends of the bar so that it will have sharp cutting edges along the ends for engaging the walls of the cup, forcing the bar downwardly in the cup diametrically across it, the length of the bar being slightly greater than the diameter of the cup so that the sharp cutting edges of the bar are caused to cut into the walls of the cup throughout the distance the bar 30 is forced into the cup, the engaging of the sharp cutting edges of the bar and the walls of the cup preventing forced rotation of the bar in relation to the cup.

5. The method of fixing a turning means 35 within the cup portion of a cup-shaped bung, which comprises making a bar of a length sufficient to extend across said cup portion, forming spaced projections along opposite end faces of said bar, forcing said bar downwardly into and 40 diametrically across the cup causing the projections on the bar ends to cut slots or grooves into the side wall of the cup, and thereafter deforming the cup wall above the bar to close said slots or grooves to prevent removal of the bar from 45 the bung.
